[57] CLAIM

The ornamental design for a dental material curing apparatus, as shown and described.

DESCRIPTION

FIG. 1 is a top, front and right side perspective view of a dental material curing apparatus showing our new design, on a reduced scale;

FIG. 2 is a plan view thereof;

FIG. 3 is a left side elevational view thereof;

FIG. 4 is a right side elevational view thereof;

FIG. 5 is a bottom view thereof;

FIG. 6 is a front elevational view thereof; and,

FIG. 7 is a rear elevational view thereof.

The cords are omitted in FIGS. 2 through 7 for convenience of illustration.
